CHANGEABLE SIGN

Filed Dec. 17, 1928

Inventor
W. Little

By his Attorney
J. Ledermann

UNITED STATES PATENT OFFICE

WILLIAM LITTLE, OF BROOKLYN, NEW YORK

CHANGEABLE SIGN

Application filed December 17, 1928. Serial No. 326,437.

The main object of this invention is to provide a menu card in which the characters inscribed thereon may be changed from day to day in a convenient manner without replacement of any of the parts of the card.

Another object of this invention is to provide a menu card consisting of a hollow frame in which a plurality of spindles having pulleys thereon are mounted, the pulleys having curtains trained about them, and these curtains are provided with sets of characters, one of which is adapted to be exposed through a slot in the panel of the device.

The above and other objects will become apparent in the description below, in which characters of reference refer to like-named parts in the drawing.

Referring briefly to the drawing, Figure 1 is a front elevational view of the menu with the panel removed to expose the operating mechanism therefor.

Figure 2 is a cross sectional elevational view of the same.

Figure 3 is an external view of the menu card.

Figure 4 is an end elevational view of the same.

Referring in detail to the drawing, the numerals 10 and 11 indicate the sides of an open frame. These sides are joined by end pieces 12 and 13. Both sides of this frame are covered, the reverse side being covered

by a board 14 which is hinged to the frame piece 13, and the front is closed by a frame member 15 in a recess portion of which a panel 16, of some suitable material such as celluloid, is mounted. This celluloid panel has a permanent character, such as "Menu" and other necessary information, printed

thereon and is also provided with a plurality of horizontal slots 17 and vertical slots 18. The frame 15 is hingedly connected to the frame member 13 as illustrated in Figure 2. This entire structure may be mounted on some

sort of a pedestal which is not shown on the drawing. The side pieces 10 and 11, which form the frame, are provided with a plurality of spaced-apart openings 19. Into these openings the ends of spindles 20, 21, 22, 23 and 24 are inserted and are adapted to be

freely rotatable therein. The ends of the spindles are provided with triangular sockets 25 which are adapted to receive the end of a key of similar conformation when it is desired to rotate said spindle. The upper 55 spindle 20 and its adjacent one 21 are provided with drums 26 and 27. These drums have an endless curtain 28 trained thereabout. This curtain is adapted to have the characters "Breakfast", "Luncheon", "Dinner" and "Supper" inscribed thereon in series. The spindle 21, in addition to the drum 27, has three additional drums 29, 30 and 31 mounted thereon which are lesser in length than the drum 27. The next successive spindle 22 65 has four drums mounted thereon about which curtains 32, 33 and 34 are trained. These curtains are suspended within the frame pieces and are trained about drums at their opposite ends on the spindle 23. The narrow curtains 35 and 36 pass around the curtains 33 and 34 while the curtain 37 passes under the curtain 32 so that no part of the area of the curtain 32 is concealed by the narrow curtain 37. These curtains 37, 35 and 75 36 and 38 at their lower ends are trained about the lowermost spindle 24. In addition to these curtains mentioned two rigidly fixed curtains 39 and 40 are located in the frame. These two latter curtains are rigidly mounted in place and are immovable, being suspended from a yoke 41.

When the panel 16 in the hinged frame is affixed in place over the front of the main frame in which the mechanism is located, 85 characters will be exposed through the slots 17 and 18. The characters exposed through the slots 18 are permanent and indicate such foods as are termed "Special" or the like. The characters on the curtains 34, 32 and 33 are in 90 a prearranged group, as the characters which appear through one slot are changed the characters in all the successive slots in the same row are likewise changed, thereby requiring that the characters be changed in 95 groups. As a key, having a triangular end, is inserted into the sockets 25 of the ends of the spindle and rotated, the curtains will be paid out from one drum to an opposite drum or taken up in the reverse direction. The 100

narrow curtains 36, 38 and 35 are adapted to carry the prices of the commodities mentioned on the larger curtains 32, 33 and 34, are located upon these larger curtains, and at the right-hand side thereof, and are independent of the larger curtains. It may be desired that door panels such as indicated by the numeral 15 are to be used on both faces of the frame. When such is the case, some of the curtains must have an exposed surface on both sides within the chamber of the frame. The curtains such as indicated by the numeral 37 are adapted to face and be visible thru the apertures 17 in the panel on the reverse face of the frame.

It is to be noted that certain changes in form and construction may be made without departing from the spirit and scope of the invention.

I claim:—

In a device of the class described, a skeleton frame, a panel covering said skeleton frame and having slots therein, endless curtains mounted in said skeleton frame, spindles rotatable in said frame, drums rigid on said spindles having said curtains trained thereabout, yokes rigidly mounted in said frame having said curtains suspended therefrom, said spindles being rotatably anchored in said frame, and triangular sockets in the ends of said spindles adapted to be exposed and receive a key for rotating said spindles some of said curtains being deflected by an adjacent curtain to permit complete exposure of one side of the adjacent curtain and partial exposure of the opposite side of the adjacent curtain.

In testimony whereof I affix my signature.

WILLIAM LITTLE.
